TOOTHBRUSH

Romie H. Miller, St. Louis, Mo.

Application March 26, 1934, Serial No. 717,379

3 Claims. (Cl. 15—167)

My invention relates to a tooth brush and particularly to a brush in which the tufts forming the bristle field are so shaped as to facilitate the cleansing of those teeth surfaces which are most liable to infection and decay. Such surfaces include especially the fossæ and grooves of the occlusal faces of the teeth and the opposing surfaces between the teeth. The fossæ and grooves are all triangular, or approximately so, as are also entrances to the opposing surfaces 10 of the teeth. Therefore, in my improved kind of brush I provide a bristle field composed of tufts which are in the form of oblique prisms, each having an apex adapted to enter triangular spaces in or between the teeth and effectively remove food particles or other foreign matter from the adjacent surfaces to prevent infection and decay at these critical portions of the denture.

In the accompanying drawing Figure 1 is a plan view of a tooth brush made in accordance with my invention; Figure 2 is a side elevation of the head of the brush; Figure 3 is a sectional view, in perspective, taken on the line 3—3 of Figure 2; Figure 4 is a diagram showing the application of the brush to the lateral faces 20 of a denture; Figure 5 is a diagram showing the application of the brush to the occlusal faces 25 of a denture; and Figure 6 is a plan view showing a modified form of brush.

My brush in general form resembles the usual type of tooth brush, having a head 5 and a handle 6. The head 5 may be either slightly tapered, as shown in Figure 1, or straight, as shown in Figure 6, and the handle may be straight, bent or curved as desired. The head 30 5 carries the bristle field which is composed of a number of bristle tufts 7 secured in the head in any usual and well known manner. In the drawing I have shown twelve tufts arranged in two rows of six each but the number of tufts 35 may be varied. The tufts are arranged in two rows which may be slightly diverging, as shown in Figure 1, or may be parallel, as shown in Figure 6. The tufts are angular in cross section and preferably triangular, as shown in Figures 40 1, 2 and 3. The tufts may, however, be of other cross section than triangular, provided each tuft has at least one angle to provide an angular apex. For example, the tufts may have a cross section like that shown in Figure 6, in which 45 the cross section is that of a sector of a circle.

The free ends of the tufts are cut off in a plane inclined to the axes of the tufts to produce on each tuft an oblique, flat face 8 composed of bristle ends. These faces, in the pre-

ferred form, are triangular. In any case the tuft has an angular apex 9 which is adapted to enter a triangular recess or passage-way so that the ends of the bristles may effectively remove foreign matter from the walls of such recess or 60 passage.

Figure 4 diagrammatically illustrates the manner of applying the brush to the lateral surfaces of teeth 10 adjacent the gingival margin so that the apices of the tufts may effectively enter the angular passages leading to the opposing tooth surfaces to cleanse the same. Figure 5 is a diagram illustrating the manner of applying the brush to the occlusal faces of the teeth. In such application the oppositely inclined faces 8 70 of the two rows of tufts cooperate with the oppositely inclined walls of a tooth groove to wedge the apices 9 of the bristle tufts into the bottom of the groove, the thorough cleansing of which is essential in preventing tooth decay 75 due to the fact that the grooves often terminate in pressures resulting from imperfect union of the tooth lobes.

Having fully described my invention, what I claim as new and desire to secure by Letters 80 Patent of the United States is:

1. A tooth brush provided with a bristle field formed of tufts, said tufts being angular in cross section and having their free ends cut off in planes inclined to their axes, said planes being 85 so located as to form an apex at one angle of each tuft.

2. A tooth brush provided with a bristle field formed of two rows of tufts, said tufts being angular in cross section and being cut off in 90 planes inclined to their axes to form an apex at one angle of each tuft, the apices of both rows of tufts being located at the inner side of the row.

3. A tooth brush provided with a bristle field 95 formed of two rows of tufts, said tufts being triangular in cross section and having their free ends cut off in planes inclined to their axes to form an apex at one angle of each tuft, the apices of each row of tufts being located 100 at the inner side of the row.
